Primary Examiner — Paula Greene

(74) Attorney, Agent, or Firm — William J. Lenz, Esq.;
Neal, Gerber & Eisenberg LLP(57) **CLAIM**

The ornamental design for a microphone grille, as shown and described.

DESCRIPTION

FIG. 1 is a top perspective view of the microphone grille in accordance with a first embodiment;

FIG. 2 is a first side elevational view thereof, the opposing side being a mirror image of FIG. 2;

FIG. 3 is a second side elevational view thereof;

FIG. 4 is a third side elevational view thereof, the opposing side being a mirror image of FIG. 4;

FIG. 5 is a top plan view thereof;

FIG. 6 is a top perspective view of the microphone grille in accordance with a second embodiment;

FIG. 7 is a first side elevational view thereof, the opposing side being a mirror image of FIG. 7;

FIG. 8 is a second side elevational view thereof;

FIG. 9 is a third side elevational view thereof, the opposing side being a mirror image of FIG. 9; and,

FIG. 10 is a top plan view thereof.

The broken lines in the drawings illustrate the portions of the design that form no part of the claim.
